UNITED STATES PATENT OFFICE.

LEON ADOLPHUS HALL, OF KEENE, NEW HAMPSHIRE.

MEDICAL APPLIANCE.

1,417,318.

Specification of Letters Patent. Patented May 23, 1922.

Application filed August 13, 1920. Serial No. 403,221.

To all whom it may concern:

Be it known that I, LEON ADOLPHUS HALL, a citizen of the United States, and resident of Keene, in the county of Cheshire and 5 State of New Hampshire, have invented a new and Improved Medical Appliance, of which the following is a full, clear, and exact description.

It is well appreciated that quite a number of the human ailments are to be attributed to the irregular action of the intestines, which produce what is commonly known as constipation.

With this in view, numerous remedies 15 have been placed upon the market acting in the nature of a purgative or a regulator for the intestines, and by means of which it has been sought to induce regularity.

Most of these remedies, although offering 20 temporary relief, have resulted in increasing the sluggishness of the intestines to a point where it has been necessary to resort to the drug in ever increasing quantities to produce the result desired, thus forming a 25 habit.

It is also well understood that, with a view of overcoming the defects of the aforementioned treatment, massaging has quite often been resorted to with extremely beneficial results. However, massage has had 30 to be given by an expert and where the period of treatment extended over a length of time, the cost involved was quite large, in view of the fact that one treatment alone 35 required the application of pressure over a relatively large amount of time.

I have now discovered that massaging, i. e. a movement with pressure over the 40 surface of the intestinal cavity is not essential, but where pressure is applied without movement for a considerable length, the treatment varying from one to ten hours a day, that extremely beneficial results will be produced.

45 I have therefore invented a medical appliance by means of which continued pressure will be exerted over the sigmoid flexure, the descending colon, the ascending colon (in both of which latter a sharp turn 50 exists) and over the cæcum where the appendix is situated.

Reference is had to the attached sheet of drawings as illustrating one practical embodiment of my invention and in which, 55 Figure 1 is a front view of a torso show-

ing my improved medical appliance associated therewith.

Figure 2 is a front view of such appliance, and

Figure 3 is a sectional side view taken 60 along the lines 3—3 of Figure 2.

My appliance is preferably constructed of a single piece of material of any desired type, and includes two half sections which are joined together, each of said half sections presenting preferably identical parts for which reason it will only be necessary to describe in detail one of the same.

Referring now more particularly to Figure 2 it will be seen that in this view I have 70 utilized a medical appliance constructed in accordance with my invention, such appliance being constructed of wire, in this instance it being noted that the same may be rubber covered as has been indicated by the 75 reference numeral 5 in Figure 1.

The end portion 6 of the wire is extended in the form of a loop 7 so as to provide a medium whereby the ends of a belt 8 may be attached thereto. Thence the wire is 80 extended as at 9 to provide a portion substantially parallel to the end piece 6 of the wire. From the end of this portion the wire is extended upwardly in the form of a curve as at 10 so as to conform to the body of a 85 wearer. From the upper end of the curve portion, the wire is extended inwardly as at 11, and thence downwardly as at 12, the inner end of such downwardly extending portion lying in a substantially horizontal 90 plane as at 13 to a point at which it lies adjacent the smaller portion of the opposite half section.

The appliance further includes a substantially vertical extending portion 14 forming 95 a continuation of the horizontal portion 13, the upper end of said vertical portion being provided with an outwardly extending part 15 from whence the wire extends downwardly as at 16, terminating in 100 a horizontal portion 17, which latter portion is continued and forms the connection between a smaller half section.

It will now be noted that the appliance 105 aforesaid is conveniently retained in applied position by means of the belt 8 and a further belt 18, which latter belt has its ends affixed to the substantially vertical extending portion 14 adjacent the outwardly extending part 15.

The upper portions of the downwardly extending portion 16 and vertical part 14 overlie the stomach and serve to retain a constant pressure upon the same. The body 5 and lower portion of the downwardly extending part of the wire 16 presses against the smaller intestines. The left lower side of the appliance overlies the descending colon and sigmoid flexure, while the right 10 hand lower side of the appliance overlies the ascending colon and cæcum.

By this construction, it will be appreciated that a constant even pressure is applied to those parts of the intestine having 15 a tendency to sluggishness, and it has been found by experiment, that by virtue of this pressure that the defects enumerated in the preamble of this specification are overcome, the appliance being associated with the body 20 of the wearer for that length of time which is found to be most desirable to produce benefit and results.

It will be obvious that it is within the scope of my invention to vary the dimensions and arrangements of the parts of the appliance, according to the needs of the patient, it being also understood that the same may be constructed of any desirable material, and in instances where it might prove 30 desirable, to provide a cushioning agent with the cover 5.

I claim:-

1. A medical appliance for relieving constipation, said appliance being adapted to 35 lie against and exert pressure against the intestinal cavity, said appliance including a pair of loop portions, a curved outwardly extending portion forming a continuation of each of said loop portions, and inwardly, 40 downwardly and horizontally extending portions forming a continuation of each of

said curved portions, a substantially vertical extending portion forming a continuation of said latter portion, a downwardly extending portion forming a continuation 45 of each of said vertically extending portions, a horizontal portion extending between and connecting the lower ends of each of said downwardly extending portions, and means connected to said loop portions, and 50 said vertically extending portions for retaining said appliance in intimate contact with the body to which it is applied.

2. A medical appliance for relieving constipation, said appliance being adapted to 55 lie against and exert pressure against the intestinal cavity, said appliance including a pair of loop portions, a curved outwardly extending portion forming a continuation of each of said loop portions, and inwardly, 60 downwardly and horizontally extending portions forming a continuation of each of said curved portions, a substantially vertical extending portion forming a continuation of said latter portion, a downwardly 65 extending portion forming a continuation of each of said vertically extending portions, a horizontal portion extending between and connecting the lower ends of each of said downwardly extending portions, 70 means connected to said loop portions and said vertically extending portions for retaining said appliance in intimate contact with the body to which it is applied, and outwardly extending parts forming a part 75 of said appliance, and each of said vertically extending portions, said latter outwardly extending part bearing against the retaining means having its ends secured to said vertically extending portions and holding the 80 same against movement.

LEON ADOLPHUS HALL.
